United States Patent Office

Des. 195,602
Patented July 2, 1963

195,602

COMPARTMENTED DISPLAY PACKAGING CONTAINER

John Donald Bostrom, Niles, Ill., assignor to Poster Packaging, Inc., Chicago, Ill., a corporation of Delaware
Filed Mar. 16, 1961, Ser. No. 64,336

Term of patent 14 years

(Cl. D58—11)

FIG. 4

FIG. 2

The top for the container which is shown in broken lines is plain.

The essential features of the design are shown in full lines.

I claim:

The ornamental design for a compartmented display packaging container, as shown and described.
